CLAIM

The ornamental design for a paper or towel dispenser, as shown and described.

DESCRIPTION

FIG. 1 is a perspective view of a paper or towel dispenser of the new design;

FIG. 2 is a front elevation view of the paper or towel dispenser;

FIG. 3 is a rear elevation view of the paper or towel dispenser;

FIG. 4 is a top plan view of the paper or towel dispenser;

FIG. 5 is a bottom plan view of the paper or towel dispenser;

FIG. 6 is left-side elevation view of the paper or towel dispenser; and,

FIG. 7 is right-side elevation view of the paper or towel dispenser.

The portions shown in broken lines do not form part of the design.

1 Claim, 6 Drawing Sheets

Related U.S. Application Data

a division of application No. 29/647,736, filed on May 15, 2018, now Pat. No. Des. 917,917.
